US00D794641S

(12) **United States Design Patent** (10) Patent No.: **US D794,641 S**
(45) Date of Patent: **** Aug. 15, 2017**

(54) **MEMORY DEVICE**

- (71) Applicant: **SAMSUNG ELECTRONICS CO., LTD.**, Gyeonggi-do (KR)
- (72) Inventors: **Hyo-jae Bang**, Hwaseong-si (KR); **Do-geun Kim**, Seoul (KR); **Hong-kyun Kim**, Seongnam-si (KR); **Young-bok Jeon**, Seoul (KR)
- (73) Assignee: **SAMSUNG ELECTRONICS CO., LTD.**, Suwon-si (KR)
- (**) Term: **15 Years**
- (21) Appl. No.: **29/553,613**
- (22) Filed: **Feb. 3, 2016**

Related U.S. Application Data

- (63) Continuation-in-part of application No. 14/622,328, filed on Feb. 13, 2015, which is a continuation-in-part (Continued)

CLAIM

The ornamental design for a memory device, as shown and described.

DESCRIPTION

FIG. 1 is a perspective view of a memory device showing our new design; and,

FIG. 2 is a top plan view thereof.

The broken lines and unshaded portions contained within broken lines throughout the drawings, depict exemplary parts of the memory device that are shown for illustrative purposes only, and do not form part of the design claim.

1 Claim, 2 Drawing Sheets

Related U.S. Application Data

of application No. 13/678,115, filed on Nov. 15, 2012, now Pat. No. 8,982,567, which is a continuation-in-part of application No. 12/349,678, filed on Jan. 7, 2009, now abandoned.
